HENRY N. MCKAY, OF OAKLAND, CALIFORNIA, ASSIGNOR TO THE WAHL COMPANY, OF WILMINGTON, DELAWARE, A CORPORATION OF DELAWARE.

TOTAL-PROOF LOCK FOR COMPUTING TYPE-WRITERS.

1,274,731.

Specification of Letters Patent.

Patented Aug. 6, 1918.

Application filed May 31, 1916. Serial No. 100,990.

To all whom it may concern:

Be it known that I, HENRY N. MCKAY, a citizen of the United States, residing at Oakland, in the county of Alameda and State 5 of California, have invented new and useful Improvements in Total-Proof Locks for Computing Type-Writers, of which the following is a specification.

This invention relates to a total proof 10 lock for computing typewriters.

The purpose of this device is to prove the correctness of the transcription of a total shown in a totalizer of a computing type-writing machine, such as is shown in the 15 copending application of John C. Wahl, Serial No. 84,340, filed March 15, 1916.

At present in key-actuated computing typewriters which clear back to zero by direct subtraction or complementary addition, 20 it is possible for an operator by mistake to copy a wrong total on the paper even though the correct total be shown in the totalizer, and then to proceed with a new computation without noting the error. Any digits remaining 25 in the totalizer after such error cause the next computation to show a wrong result, thus creating a double error. Many mistakes are thus made, since accuracy of work depends on the care of the operator 30 only, and correctness depends on a human element which may vary.

An object of the invention is to cause the 35 keys of a computing typewriter to become automatically locked against further operation after typing a wrong total and simultaneously to display both a visible and an audible signal, thus immediately calling the attention of the operator to the error. Further objects will hereinafter appear.

40 The invention consists of the parts and the construction and combination of parts as hereinafter more fully described and claimed, having reference to the accompanying drawings in which—

45 Figure 1 is a front view of the main carriage truck of a "Remington" typewriter showing the application of a "Wahl" adding and subtracting mechanism and also showing the application of the present invention.

50 Fig. 2 is a cross section on line 2--2 of Fig. 1.

Fig. 3 is a perspective view of the pick-up lug carried by each totalizer and one end of the arm which it engages. 55

Fig. 4 is an enlarged front view of the cross truck actuator, showing the front covering removed and partly broken away.

Fig. 5 is an illustration of one form of work produced by the present machine. 60

Fig. 6 is a side elevation of Fig. 4, showing the right-hand side plate, indicated at 20, removed.

Fig. 7 is a side elevation of one of the totalizer gears. 65

Fig. 8 is a longitudinal section through one set of totalizer gears, showing all the deep notches in alignment with relation to the depressible dog.

Fig. 9 is a similar view, showing all but 70 one of the deep notches in alignment with relation to the depressible dog.

Fig. 10 is a perspective view of the sliding link.

Fig. 11 is a perspective view of the combined resetting lever and error signal. 75

Fig. 12 is a front view of the key-lever locking-bar shown in Fig. 6.

Fig. 13 shows a modified form of a key-lever locking mechanism. 80

Fig. 14 is a cross-section of the main actuator, showing the connection with the numeral keys.

Referring to the drawings in detail, 2 indicates the main totalizer truck mounted on the carriage of a "Remington" typewriter upon which is applied a "Wahl" adding and subtracting mechanism and particularly a model of same known as the "cross-footing machine." This computing mechanism 90 consists, in this instance, of a main actuator 3, secured to the frame of the typewriter in the usual manner and 3 totalizers, A, B, and C, operable in conjunction therewith, which are mounted on the main truck (2), and also 95 consists of a sub-actuator 4 and a totalizer D, operable in conjunction therewith which is mounted upon a subtruck 5, called a cross-truck. This cross-truck moves across the actuator 4 in unison with any of the totalizers shown at A, B, and C, when these move across the actuator 3, and it is automatically returned to inoperative position, with relation to the actuator 4, the moment

any of the totalizers A, B, or C move out of engagement with the actuator 3.

This is accomplished in the following manner: Pivotedly secured, as at 6, upon a lug 7 secured to the cross-truck 5 is an arm 8, the opposite end of which is shown in Fig. 3. This end of the arm is provided with an upwardly projecting lug 9 which is adapted to be engaged by a pick-up lug 10 projecting downwardly from each totalizer A, B, and C, as shown in Figs. 3 and 6.

Movement of the main carriage truck 2 in the direction of arrow *a* will first cause the first totalizer A to move into register with the actuator 3. The pick-up lug 10, mounted on the totalizer A, will simultaneously engage with the lug 9 formed upon the arm 8 and will, therefore, cause the cross-truck and totalizer D to move across its coöperating actuator 4 in unison with the arm 8. This unitary movement of the totalizers A and D and the main carriage truck 2 and the cross-truck 5 takes place as long as the totalizers are in engagement with their coöperating actuators but no longer, as the cross-truck 5 will become automatically released the moment the totalizers A and D move out of engagement with their actuators.

This is accomplished as follows: Formed on one side of arm 8 is a pin 11 which projects through a slot 12 formed in a cam track 13. This pin engages with a downwardly sloping cam surface 14, formed in the slot 12, the moment the totalizers A and D move out of engagement with the actuators, and therefore causes the arm 8 to become depressed about the pivot 6 and will consequently cause the projection 9 to move out of engagement with the pick-up lug 10 to a position where the arm is released, thus permitting the cross-truck to return to normal position. This movement of the cross-truck, when arm 8 is released with relation to a pick-up lug, is transmitted through a coil spring 16 attached to one end of the cross-truck. Continued movement of the main carriage truck will next bring the totalizer B into register with the actuator 3 and the pick-up lug 10 carried by the totalizer B will simultaneously engage the projection 9 on arm 8 and again cause the cross-truck and totalizer D to move in unison with the main carriage truck and the totalizer B until releasing position is again reached, *i. e.*, when pin 11 engages with the cam surface 14, which, as previously stated, takes place when one of the totalizers A, B or C move out of engagement with the actuator 3.

It can thus be seen that the totalizer D will, in the present instance, move across its coöperating actuator 4 three times as the arm 8, connected to its cross-truck, is picked up three times by the totalizers shown at A, B and C and that the totalizer D, with connected cross-truck will also be automatically

returned across the actuator 4 three times as the arm 8 is automatically released by the cam 14, thus permitting the spring 16 to retract the cross-truck and totalizer D each time.

The mechanism so far illustrated and described is a duplication of the mechanism employed in the model of a "Wahl" adding and subtracting mechanism known as the "cross footing machine", as applied to the Remington typewriter. This mechanism operates to such an extent with the several parts of the present attachment that a description of same has been made to make more readily comprehensible the remaining mechanism, which comprises the novel improvements of this invention.

Mounted in alignment with the teeth of the master gear 17 of the actuator 4 is a depressible dog, 18. This dog forms one of the most important features of the present invention as it, together with the totalizer gears indicated at 19 in Figs. 7, 8 and 9, provides the means whereby the keys of the typewriter are locked when an incorrect transcription or error is made. The depressible dog is slidably mounted in a bearing 21 secured on the right-hand side-plate 20 of the actuator 4. The upper end of the dog is slotted, as at 22, to straddle the master-gear shaft 23, and a spring 24 attached to a pin at one end and to the depressible dog at the other end normally holds the dog in the raised position shown in Fig. 6, in which normal position it is at a sufficient height so that it will be depressed by the passage of any normal notch of a totalizer gear. Each totalizer gear mounted in the totalizer D and operating in conjunction with the actuator 4 and the depressible dog 18 is provided with three or more notches 25 having a greater depth than those notches which are the normal depth of the gear teeth indicated at 26. These deep notches will not depress the dog 18 and this fact makes possible the proof of totals later to be described.

From the description previously made, it will be remembered that the totalizer D moves across the actuator 4 in unison with each of the totalizers, indicated at A, B and C, and also that the totalizer is automatically returned with the cross-truck 5, by means of the retracting spring 16, when the arm 8 is released. It can thus be seen that all the totalizer gears, here shown as being 9 in number (see Figs. 8 and 9) have to travel back and forth across the depressible dog 18 and the main driving gear 17 of the actuator 4 during the operation of the computing mechanism as a whole. This transverse movement of the totalizer D is utilized to operate a mechanism which, under certain predetermined conditions, is made to lock the typewriter keys when an error is 130

made. This is accomplished as follows: 27 represents the rocker-shaft in the actuator 4 which is operated by the numeral keys 80 whenever they are depressed while the computing mechanism is in use. Secured on one end of said rocker-shaft is a projecting lug 28, and pivotally mounted on the side plate 20, as at 29, is a blocking latch 30, the lower end of which is adapted to be moved into and out of engagement with the lug 28. Engageable with the upper end of the latch 30 is a coöperating latch 31, pivotally mounted on the side plate as at 32. This latch normally engages the upper end 15 of latch 30 to hold the lower end of said latch out of engagement with relation to lug 28. This is accomplished by attaching a spring 33 to the opposite end of a latch 31. Slidably mounted between the side plate 20 and the opposite plate 20^a of the actuator 4, at right angles to the plane of the coöperating latches 30 and 31 and the lower end of the depressible dog 18, is a sliding link 34 (see Figs. 4 and 10) and pivotally 25 mounted, as at 35, at one end of said sliding link is a filler plate 36 which, during certain predetermined time intervals, is adapted to occupy a position intermediate of the latch 31 and the lower end of the depressible dog 18. The depression of the dog, when this 30 filler plate is in such intermediate position will trip the latch 31 or move it out of engagement with relation to latch 30 and will simultaneously permit the latch 30 to assume the dotted line position indicated at 30^a where it would engage the lug 28, thus locking the rocker-shaft 27 against movement and all of the numeral keys against movement as these are directly connected with 35 the rocker shaft as shown in Fig. 14.

Secured to shaft 29 is a re-setting lever 37, one end of which projects through the actuator casing, as indicated at 38, this serves also as a visual error signal. Said lever normally assumes the full line position shown in Fig. 6 and the outer end is then concealed by a closure or cap 39. Any movement of the latch 30 from the full line to the dotted line position shown causes the resetting lever 50 to move in unison with same to assume the dotted line position indicated at 38^a where it produces both a visible and, as hereinafter described, an audible signal to the operator that an error has been made. The typist 55 may thus correct the error before any harm results from it.

The manner of making the correction will be described later.

In order to illustrate more clearly the operation of the machine and the value of this device, a sample of one of the many classes of work accomplished by the present machine is shown in Fig. 5. This shows a statement designed to have items added to it from day to day, and which it is desired

to keep totaled at all times, so that the last amount in the "new total" column will always show the sum of all items entered on the statement to date. This is accomplished by writing the previous or old total after 70 entering a new item, and having the computing mechanism indicate in the cross footing totalizer D the sum of the old total plus the item, which of course is the new total required, and is written in the new total 75 column.

To handle the above class of typical problems, an equipment of totalizers is used such as are illustrated in the drawings shown herewith. The totalizers, A, B and C, which 80 are termed the vertical totalizers, cover respectively columns a, b and c on the statement illustrated, and their purpose is to accumulate the sums of all amounts typed in their respective columns, sums to be used 85 for proving the work and not having to do directly with the present case. Totalizer D, as previously described, covers each column successively, and its purpose is to combine an amount typed in column a with an 90 amount typed in column b, showing a sum to be typed in column c.

In other words, any amount typed in column a accumulates in totalizers A and D. Any amount typed in column b accumulates 95 in totalizers B and D. After typing one amount in each of these columns, totalizer D will show the sum of these two amounts, which sum is then typed in column c, whereupon the totalizer D will be cleared or 100 brought back to all zeros by subtraction, provided said sum be typed correctly.

If incorrectly typed, totalizer D will not be cleared, but will contain certain remaining digits, and a new total other than the 105 true one will be shown in error on the statement form, causing either an overcharge or an undercharge against a customer, if this error be not noted by the operator. This remainder will also cause any subsequent 110 computation to show an equivalent error.

It is to guard against these possibilities of error that the present invention has been developed.

With a statement such as illustrated inserted in the machine, the operator will proceed as follows: After typing the date and detail of the first item, the amount of this item, which is \$10.00 is typed in column a, and is added both in totalizer A and in the cross-footing totalizer D. This being the first item, there is therefore no old total to be typed, and this amount of \$10.00 is the first total and is written down in column c, the new total column. Totalizer D returns 125 to zeros since the amount was correctly typed. At a later date the statement is reinserted in the machine and the second item is added to it. The operator as before types the date and detail of the second item and 130

enters the amount of the second item, which is \$15.00, in column *a*, and then copies from the line above the first total, or \$10.00 in column *b*, whereupon totalizer D shows the combined sum of these two amounts, or \$25.00. On correctly typing this sum in column *c*, totalizer D returns to zeros as before.

The computing mechanism is automatically or manually actuated before each total is written in column *c* so as to change the controlling gears in the actuator 4 to subtract position.

As illustrated in Fig. 5, the totalizer gears 19 of the totalizer D have certain notches 25 cut deeper or larger than the remaining notches. These deep notches 25 are the only notches in these gears of sufficient depth or size to clear the dog 18 in passage, without depressing it. These deep notches are so positioned that a complete series of them will be lined up as in Fig. 8, opposite the depressible dog 18 when, and only when, a series of all zeros is shown in the number wheels of the totalizer D. When all deep notches are thus in line, the totalizer D may be retracted across the depressible dog after typing an amount without causing the dog to be depressed. Since any error made in the transcription of the new total from totalizer D in column *c* will cause one or more digits to remain in the number wheels of the totalizer, it follows that all the deep notches will not be in line and that certain small notches will be left in line with the dog 18, as in Fig. 9, thus causing the dog to be depressed when the totalizer is retracted by its spring across the dog.

Since the depressible dog 18 will be depressed whenever totalizer D is retracted with an amount shown therein, and since in the illustrated work of the machine it is necessary that totalizer D be retracted while containing an amount after typing in either column *a* or column *b*, it is evident that the dog 18 must be depressible in these columns without releasing the co-operating latches 30 and 31, but that means must be provided so that depression of the dog 18 after operating in column *c* will cause the latches to be released.

This is accomplished in the following manner:

Secured to the last vertical totalizer C is a cam projection 40, and pivotally mounted on one end of the actuator 3 is a bell-crank 41. One end of the bell-crank is so positioned as to be engaged by the cam 40 at a predetermined time period during the movement of the totalizer C across the actuator 3 or when the last numeral wheel or totalizer reaches printing position, and moves into engagement with the master gear in the actuator. Depression of a nu-

meral key in this last space of the totalizer C, as before described, automatically releases the cross-truck which returns to rest position at the right side of the depressible dog 18. The depression of the bell-crank 41, by means of the cam 40, causes the sliding link 34 (see Figs. 4 and 10) to move in the direction of arrow *d* a sufficient distance to bring the filler plate 36 into alignment between the lower end of the depressible dog and the latch 31. This movement of the sliding link takes place in unison with the depression of the bell-crank 41 as the bell-crank is directly connected with the sliding link through means of a centrally pivoted lever 42 and a link 43 (see Fig. 1). If, therefore, an error is made when typing in column *c* the total accumulated in totalizer D, one or more digits will remain in totalizer D instead of all zeros. The deep notches in the totalizer gears 19 will therefore not align and the smaller notches left by the error will cause the dog 18 to become depressed when the cross-truck is released and retracted to rest position on the right side of the dog. The release and return movement of the cross-truck, carrying the totalizer D, takes place during the time period when the bell-crank 41 is depressed by the cam 40 and when the filler plate 36 is in alignment between the lower end of the depressible dog and the latch 31. The depression of the dog will, therefore, rock the pivotally mounted filler plate 36 and cause this to depress the latch 31, which, in turn, releases the latch 30, permitting this to move into engagement with the lug 28 and lock the rocker-shaft 27, together with the directly connected numeral keys, against movement. The resetting and signal lever 37 will simultaneously move into display position, thus giving visual signal of error. An audible signal will also be given as the lever 37, in its movement from the full line position to the dotted line position shown in Fig. 6, engages the clapper 50 of a bell 51 carried by the actuator 4.

Means have thus been provided for locking the numeral keys against further operation if an error is made, and for simultaneously displaying a visible signal and giving an audible alarm, making it impossible for the operator to proceed without noting the mistake. As a further means to prevent continued operation of the machine, should the operator fail to hear the audible warning or see the visible error signal, means have been provided for locking the remaining keys of the typewriter. This is accomplished in one instance by forming a projection 53 on the lower side of each letter key-lever 54 and by pivotally mounting, below the key bars 54, a bail-shaped cross-bar 55 which will be projected into the path

of movement of the projections 58 when the signal lever 37 is moved to display position. This is accomplished by securing a crank-arm on the shaft 56 which carries a bail 55 and connecting said crank with the signal lever 37 by means of a link 57. It is thus possible to lock all the keys against movement and simultaneously to give an audible signal and a visible indication.

10 Further operation of the machine is positively prevented until the error is noted for correction.

Correction is accomplished in the following manner: The operator, having been notified of the error, manually raises the resetting lever 37 to its rest position under the concealing cap 39, said cap acting as a stop also to the movement of the hand. The resetting lever, being rigidly connected to the 20 latch 30 through the shaft 29, in its return movement restores latch 30 to its original position, where it is again held by the cooperating latch 31, which again resumes its original position impelled by its spring 33. 25 By this operation all warning signals are manually removed, and the machine is again operable. The operator then corrects the error in the usual manner provided for the purpose in such machines, which is by 30 manually reversing the controlling gears of the actuators, repeating the error, thus restoring the correct amount to the totalizers wrongly operated in, and then, after necessary erasure, copying the total correctly. A 35 second error will cause a second lock.

Inexperienced operators have not infrequently been known to make the mistake of neglecting to copy the correct amount after having performed the first part of the correction operation and having restored the right amount to the totalizer. This oversight is prevented by the invention above described since the machine becomes locked against operation and the various error signals are again shown when the totalizer D re-crosses its actuator with the correct amount shown in it. A second manual resetting of the lever 37 is required before writing the final correct total, and if this 50 is neglected the locked condition of the key-levers will bring the oversight to the operator's attention on attempting to write any letter or figure of a succeeding piece of work.

55 A modification of the key-lever locking mechanism shown by reference characters 53 and 54 is shown in Fig. 13. The shaft 56 is here provided with a plurality of comb-like projections 58 which are adapted to be moved into or out of the path of travel of pins 59 secured one on each key-bar 54. This mechanism may be preferable as it permits a more compact arrangement than that shown in Fig. 6.

60 Since it may at times be necessary or de-

sirable to be able to type amounts in any or all columns and accumulate their sum in totalizer D, and since it would be inconvenient to have the machine lock repeatedly in certain columns, means have therefore been provided for making the entire device 70 inoperative at will.

This is accomplished as follows:

Slidably mounted on the inner side of the cover inclosing the actuator 4 is a shoe 76, 75 see Figs. 1 and 6. This shoe is provided with a knob 77 projecting through a slot 78 formed in the cover. If it is desired to render the automatic locking mechanism inoperable, it is only necessary to grasp the knob 77 and move the shoe in the direction of arrow k until the forward end of the shoe projects under the resetting lever 38 as shown in Fig. 6. This locks the lever with connected shaft 29 and latch 30 against movement and therefore renders the locking mechanism inoperable. The dog 18 may, however, be depressed and the latch 31 rocked about its pivot 32 without releasing the latch 30 as the latch 30 is secured 80 to the shaft 29 and as the shaft 29 carries the resetting lever 38, which in this instance is locked, it will be seen that the locking mechanism, as a whole, is rendered inoperable.

95 The depressible dog is here shown as carried by the actuator 4. This arrangement may, however, be modified as it may be mounted on either actuator and may be operated by any totalizer.

100 Having thus described my invention, what I claim and desire to secure by Letters Patent is—

1. In a computing typewriter, the combination of a set of digit keys, a traveling 105 carriage, a totalizer, an actuating mechanism to operate said totalizer, and means operable by the totalizer and brought into operation when said traveling carriage has reached a particular position for proving 110 the correct transcription of a total shown in the totalizer.

2. In a computing typewriter having a recording mechanism and a calculating mechanism and certain keys operating the 115 recording mechanism only and other keys common to both mechanisms, the combination with the calculating mechanism of means operative on transcribing a wrong result of a calculation for locking against 120 further operation the keys operating the recording mechanism.

3. In a computing typewriter having a recording mechanism and a calculating mechanism and certain keys operating the 125 recording mechanism only and other keys common to both mechanisms, the combination with the calculating mechanism of means operative on transcribing a wrong result of a calculation for locking against 130

- further operation, both the keys operating the recording mechanism and the keys operating the calculating mechanism.
4. In a computing typewriter having a recording mechanism and a calculating mechanism and certain keys operating the recording mechanism only and other keys common to both mechanisms, the combination with the calculating mechanism of means operative on transcribing a wrong result of a calculation for locking against further operation, the keys operating the calculating mechanism.
5. In a computing typewriter, the combination with the numeral keys, the carriage, the actuating mechanism and the totalizer therefor, of means controlled by the totalizer for automatically displaying a visible signal when a wrong total is copied from the totalizer.
6. In a computing typewriter the combination with the numeral keys, the carriage, the actuating mechanism and the totalizer therefor, of means controlled by the totalizer for giving an audible signal when a wrong total is copied from the totalizer.
7. In a computing typewriter the combination with the numeral keys, the carriage, the actuating mechanism and the totalizer therefor, of means controlled by the totalizer for locking the actuating mechanism against further operation when a wrong total is copied from the totalizer.
8. In a computing typewriter the combination with the numeral keys, the carriage, the actuating mechanism and the totalizer therefor, of means controlled by the totalizer for locking the actuating mechanism against further operation when a wrong total is copied from the totalizer and means for manually releasing said lock.
9. In a computing typewriter the combination with the numeral keys, the carriage, the actuating mechanism and the totalizer therefor, of means controlled by the totalizer for locking the numeral keys against further operation when a wrong total is copied from the totalizer.
10. In a computing typewriter the combination with the numeral keys, the carriage, the actuating mechanism and the totalizer therefor, of means controlled by the totalizer for locking the numeral keys against further operation when a wrong total is copied from the totalizer and means for manually releasing said lock.
11. In a computing typewriter, the combination with the numeral keys, the carriage, the actuating mechanism and the totalizer therefor, of means controlled by the totalizer for displaying a visible signal when a wrong total is copied from the totalizer, and means for manually removing the visible signal.
12. In a calculating machine, the combination with a set of digit keys, actuating mechanism, a plurality of totalizers co-operating with said actuating mechanism and adapted to compute numbers in a series of vertical columns, a cross totalizer adapted to perform horizontal addition, means to bring said cross totalizer successively into co-operation with said vertical totalizers, and means controlled by said cross totalizer for automatically displaying a visible signal when a wrong total is copied from said cross totalizer.
13. In a typewriter calculating machine, the combination of a set of digit keys, actuating mechanism, a plurality of vertical totalizers, a traveling carriage to bring said totalizers successively into co-operation with said actuating mechanism, a cross totalizer adapted to be brought into co-operation with said actuating mechanism concurrently with said vertical totalizers, and means controlled by said cross totalizer for giving an audible signal when a wrong total is copied from said totalizer by said digit key.
14. In a typewriter calculating machine, the combination of a set of digit keys, a traveling carriage, a plurality of vertical totalizers mounted on said traveling carriage, actuating mechanism, a cross totalizer, means to bring said cross totalizer into co-operation with any of said vertical totalizers when said vertical totalizers are actuated by said actuating mechanism, and means controlled by said cross totalizer for locking said actuating mechanism against further actuation when a wrong total is copied from said cross totalizer by means of said digit keys.
15. In a typewriter calculating machine, the combination of a set of digit keys, a traveling carriage, a plurality of vertical totalizers mounted on said traveling carriage, actuating mechanism, a cross totalizer, means to bring said cross totalizer into co-operation with any of said vertical totalizers when said vertical totalizers are actuated by said actuating mechanism, means controlled by said cross totalizer for locking said actuating mechanism against further actuation when a wrong total is copied from said cross totalizer by means of said digit keys.
16. In a typewriter calculating machine, the combination of a set of digit keys, a traveling carriage, a plurality of vertical totalizers mounted on said traveling carriage, actuating mechanism, a cross totalizer, means to bring said cross totalizer into co-operation with any of said vertical totalizers when said vertical totalizers are actuated by said actuating mechanism, and means controlled by said cross totalizer for locking one of said digit keys against further operation when a wrong total is copied from said totalizer by means of said keys.

17. In a computing typewriter the combination with the numeral keys, the letter keys, the carriage, the actuating mechanism and a plurality of totalizers therefor of means controlled by a totalizer for locking the actuating mechanism against further operation when a wrong total is copied from a totalizer and means for manually releasing said lock. 70
18. In a typewriter calculating machine, the combination of letter keys, digit keys, a traveling carriage, a plurality of vertical totalizers, the relation of said vertical totalizers and said actuating mechanism being such that the point of operation of said actuating mechanism on said vertical totalizers is determined by said traveling carriage, a cross totalizer adapted to be actuated by said actuating mechanism simultaneously with the actuation of any of said vertical totalizers, and means controlled by said cross totalizer for locking said letter keys against further operation when a wrong total is copied from said cross totalizer. 75
19. In a computing typewriter the combination with the letter keys, the carriage, the actuating mechanism and a plurality of totalizers therefor of means controlled by a totalizer for locking the letter keys against further operation when a wrong total is copied from a totalizer and means for manually releasing said lock. 80
20. In a computing typewriter the combination with the numeral keys, the letter keys, the carriage, the actuating mechanism and a plurality of totalizers therefor of means controlled by a totalizer for locking both the numeral keys and letter keys against further operation when a wrong total is copied from a totalizer. 85
21. In a computing typewriter the combination with the numeral keys, the letter keys, the carriage, the actuating mechanism and a plurality of totalizers therefor of means controlled by a totalizer for locking both the numeral keys and letter keys against further operation when a wrong total is copied from a totalizer and means for manually releasing said lock. 90
22. In a computing typewriter the combination with the keys, the carriage, the actuating mechanism and the totalizers therefor of means for displaying a visible signal when a wrong total is copied from a totalizer. 95
23. In a computing typewriter the combination with the keys, the carriage, the actuating mechanism and the totalizers therefor of means for producing an audible signal when a wrong total is copied from a totalizer. 100
24. In a computing typewriter the combination with the keys, the carriage, the actuating mechanism and the totalizers therefor of means for locking the actuating mechanism against further operation when a wrong total is copied from a totalizer. 105
25. In a computing typewriter the combination with the keys, the carriage, the actuating mechanism and the totalizers therefor of means for locking the actuating mechanism against further operation when a wrong total is copied from a totalizer and means for manually releasing said lock. 110
26. In a computing typewriter the combination with the keys, the carriage, the actuating mechanism and the totalizers therefor of means for locking the numeral keys against further operation when a wrong total is copied from a totalizer. 115
27. In a computing typewriter the combination with the keys, the carriage, the actuating mechanism and the totalizers therefor of means for locking the numeral keys against further operation when a wrong total is copied from a totalizer and means for manually releasing said lock. 120
28. In a computing typewriter the combination with the numeral keys, the letter keys, the carriage, the actuating mechanism and a plurality of totalizers therefor of means for locking the letter keys against further operation when a wrong total is copied from a totalizer. 125
29. In a computing typewriter the combination with the numeral keys, the letter keys, the carriage, the actuating mechanism and a plurality of totalizers therefor of means for locking the letter keys against further operation when a wrong total is copied from a totalizer and means for manually releasing said lock. 130
30. In a computing typewriter the combination with the numeral keys, the letter keys, the carriage, the actuating mechanism and a plurality of totalizers therefor of means for locking both the numeral and letter keys against further operation when a wrong total is copied from a totalizer. 135
31. In a computing typewriter the combination with the numeral keys, the letter keys, the carriage, the actuating mechanism and the totalizers therefor of means operable in the event of transcribing a wrong total from a totalizer for locking the actuating mechanism, the numeral keys and the letter keys against further operation and means operable in conjunction therewith for producing both a visible and an audible signal. 140
32. In a computing typewriter the combination with the numeral keys, the letter keys, the carriage, the actuating mechanism and the totalizers therefor of means operable in the event of transcribing a wrong total from a totalizer for locking the actuating mechanism, the numeral keys, and the letter keys against further operation, means operable in conjunction therewith 145

for producing both a visible and audible signal and means for manually releasing the key-locking mechanism and for removing the signals.

- 5 33. In a computing typewriter the combination with the numeral keys, the letter keys, the carriage, the actuating mechanism and the totalizers therefor of means operable in the event of transcribing a wrong 10 total from a totalizer, for locking the actuating mechanism, the numeral keys, the letter keys against further operation, means operable in conjunction therewith for producing both a visible and audible signal and 15 means for rendering all said locks and signals inoperable except at predetermined points along the writing line of the typewriter.

34. In a computing typewriter the combination with the numeral keys, the letter keys, the carriage, the actuating mechanism and the totalizers therefor of means operable in the event of transcribing a wrong 20 total from a totalizer for locking the actuating mechanism, the numeral keys, the letter keys against further operation, means operable in conjunction therewith for producing both a visible and audible signal, means for manually releasing the locking 25 mechanisms and for removing the signals, and means for rendering all said locks and signals inoperable except at predetermined points along the writing line of the typewriter.

35. In a computing typewriting machine the combination with the keys and carriage thereof and the actuating mechanism of a depressible dog carried by the actuating mechanism, and a plurality of carrying gear 40 wheels having a plurality of shallow and deep notches formed therein, carried by a totalizer having a laterally changeable relation to the actuating mechanism, each of said gear wheels adapted to depress the dog 45 during a change in said lateral relation when a small notch is in alinement therewith but incapable of depressing the dog when a deep notch is in alinement with the dog.

50 36. In a computing typewriting machine the combination with the keys and carriage therefor of a totalizer having a plurality of numeral wheels and carrying gear wheels mounted therein; an actuating mechanism 55 operable in conjunction with the totalizer, and bearing a laterally movable relation to it and a member adapted to be depressed by the said totalizer gear wheels in passage when the numeral wheels bear certain relations to each other and non-depressible by 60 said gear wheels in passage when said numeral wheels have certain other predetermined positions with relation to each other.

- 55 37. In a computing typewriting machine the combination with the keys and carriage

therefor of totalizers having a plurality of numeral wheels and gear wheels mounted therein; an actuating mechanism operable in conjunction with the totalizers, and bearing a laterally movable relation to it, and a member adapted to be depressed by the totalizer gear wheels in passage when the numeral wheels bear certain relations to each other and non-depressible by said gear wheels in passage when said numeral wheels have certain other predetermined positions with relation to each other and means controlled by depression of said member for locking the numeral keys against further operation.

- 80 38. In a computing typewriting machine the combination with the keys and carriage therefor of totalizers having a plurality of numeral wheels and gear wheels mounted therein; an actuating mechanism operable 85 in conjunction with the totalizers, and a member adapted to be depressed by the totalizer gear wheels in passage when the numeral wheels bear certain relations to each other and non-depressible by said gear 90 wheels in passage when said numeral wheels have certain other predetermined positions with relation to each other and means controlled by depression of said member for locking both the numeral and letter keys of 95 the typewriter and simultaneously displaying a visible signal.

39. In a computing typewriting mechanism the combination with the carriage; the actuating mechanism therefor and its 100 master gear wheel, of a totalizer having a plurality of gear wheels mounted therein, each of said gear wheels being provided with one or more notches of greater depth than the normal depth of the gear teeth, means 105 for moving the totalizer across the master gear, a depressible dog mounted adjacent the master gear adapted to be depressed by the gear wheels except when the deeper notches are in alinement therewith; a retaining 110 latch, a locking latch coacting with same, capable of blocking the operating movement of the actuating mechanism and means operable by the typewriter carriage when the same passes certain predetermined points 115 with relation to the printing point of the typewriter, to enable movement of the depressible dog to operate the retaining latch so as to release the locking latch to permit the same to move into locking position.

- 120 40. In a computing typewriting mechanism the combination with the carriage; the actuating mechanism therefor and its master gear wheel, of a totalizer having a 125 plurality of gear wheels mounted therein, each of said gear wheels being provided with a notch of greater depth than the normal depth of the gear teeth, means for laterally moving the totalizer with relation to the master gear, a depressible dog mounted ad-

- 5 jacent to the master gear adapted to be depressed by the gear wheels except when the deeper notches are in alinement therewith; a retaining latch, a locking latch coacting with same, capable of blocking the operating movement of the actuating mechanism, means operable by the typewriter carriage when the same occupies certain predetermined positions with relation to the printing point of the typewriter, to enable movement of the depressible dog to operate the retaining latch so as to release the locking latch to permit the same to move into locking position, and means for manually releasing the locking latch to released position.
- 10 41. In a computing typewriter having a recording mechanism and a calculating mechanism and certain keys operating the recording mechanism only and other keys common to both mechanisms, the combination with the calculating mechanism of means operative on transcribing a wrong result of a calculation for locking against further operation the keys operating the recording mechanism and manually controlled means for rendering said locking mechanism inoperable.
- 15 42. In a computing machine, the combination of a totalizer, locking mechanism actuated by the totalizer when said totalizer does not stand at zero to lock and render the computing mechanism inoperable, and means for rendering said locking mechanism inoperable.
- 20 43. In a computing machine, the combination of a totalizer, locking mechanism actuated by the totalizer when said totalizer does not stand at zero to lock and render the computing mechanism inoperable, and manually controlled means for rendering said locking mechanism inoperable.
- 25 44. In a computing machine adapted to compute in several columns, the combination with the actuator and totalizing mechanism thereof, of means controlled by the totalizing mechanism for locking the machine against further operation when a wrong total is transcribed, and means to make said locking means operable in certain columns and not in others.
- 30 45. In a calculating machine, the combination with digit keys, a totalizer, means for transcribing a total from said totalizer, said means being operated by said digit keys and means controlled by said totalizer for locking said digit keys when a wrong total is transcribed from said totalizer.
- 35 46. In a calculating machine, the combination of a plurality of totalizers, a set of digit keys, means for transcribing a total in certain columns, and means controlled by said totalizers for locking said digit keys when a wrong total is transcribed in a certain column.
- 40 47. In a combined typewriting and computing machine, the combination of a set of keys, a plurality of totalizers, and means controlled by said keys to transcribe a total in a certain column, and means controlled by said totalizers for locking said keys when a wrong total is transcribed in a certain column.
- 45 48. In a combined typewriting and computing machine, the combination of a set of keys, a plurality of totalizers, and means controlled by said totalizers for automatically displaying a visual warning signal when an error is made in transcribing a total.
- 50 49. In a typewriter calculating machine, the combination with a set of digit keys, a plurality of totalizers, means operated by said keys for transcribing a total, and means controlled by said totalizers for giving an audible alarm when the wrong keys have been struck in transcribing a total.
- 55 50. In a computing typewriter the combination with the main carriage truck and the cross truck of an actuator mounted adjacent each truck, a plurality of totalizers mounted on the main truck and operable in conjunction with the adjacent actuator, totalizers mounted on the cross truck and operable in conjunction with the adjacent actuator, a plurality of totalizer gears in the cross truck totalizers having small and deep notches formed therein, a dog mounted in the coöperating actuator adapted to be depressed by said notched totalizer gears except when none but the deeper notches in the gears are in alinement with the dog, means controlled by the movement of the main carriage, when at certain positions, for moving a latch member into alinement with the depressible dog to permit said latch to be depressed if the dog is depressed, and means operated by depression of said latch for locking the keys of the typewriter against movement.
- 60 51. In a computing typewriter, the combination with the numeral keys, letter keys, carriage, and actuating mechanism thereof, of one or more totalizers adapted to travel laterally across the actuating mechanism, and means operable by the lateral movement of a totalizer to prove the correct transcription of a total shown in that totalizer.
- 65 52. In a computing typewriter, the combination with the numeral keys, letter keys, carriage, and actuating mechanism thereof, of one or more totalizers adapted to travel laterally across the actuating mechanism, and means operable by the lateral movement of a totalizer to lock the numeral keys against further operation until manually released if an incorrect total is copied from that totalizer.
- 70 53. In a computing typewriter, the combination with the numeral keys, letters keys, carriage, and actuating mechanism thereof,

of one or more totalizers adapted to travel laterally across the actuating mechanism, and means operable by the lateral movement of a totalizer to lock the letter and numeral keys against further operation until manually released if an incorrect total is copied from that totalizer.

54. In a computing typewriter, the combination with the numeral keys, letter keys, carriage, and actuating mechanism thereof, of one or more totalizers adapted to travel laterally across the actuating mechanism, and means operable by the lateral movement of a totalizer to lock the numeral keys against further operation until manually released if an incorrect total is copied from that totalizer, and means to make said lock operable only at certain points of the writing line.

55. In a computing typewriter, the combination with the numeral keys, letter keys, carriage, and actuating mechanism thereof, of one or more totalizers adapted to travel laterally across the actuating mechanism, and means operable by the lateral movement of a totalizer to lock the letter and numeral keys against further operation until manually released if an incorrect total is copied from that totalizer, and means to make said lock operable only at certain points of the writing line.

56. In a computing typewriter, the combination with the numeral keys, letter keys, carriage, and actuating mechanism thereof, of one or more totalizers adapted to travel laterally across the actuating mechanism, and means operable by the lateral movement of a totalizer to display a visible mechanical signal until manually removed when an incorrect total is copied from that totalizer.

57. In a computing typewriter, the combination with the numeral keys, letter keys, carriage, and actuating mechanism thereof, of one or more totalizers adapted to travel laterally across the actuating mechanism, and means operable by the lateral movement of a totalizer to display a visible mechanical signal until manually removed when an incorrect total is copied from that totalizer and means to make said signal operable only at certain points of the writing line.

58. In a computing typewriter, the combination with the numeral keys, letter keys, carriage, and actuating mechanism thereof, of one or more totalizers adapted to travel laterally across the actuating mechanism, and means operable by the lateral movement of a totalizer to give an audible warning when an incorrect total is copied from that totalizer.

59. In a computing typewriter, the combination with the numeral keys, letter keys, carriage, and actuating mechanism thereof, of one or more totalizers adapted to travel laterally across the actuating mechanism, and means operable by the lateral movement of a totalizer to give an audible warning when an incorrect total is copied from that totalizer and means to make said warning operable only at certain points of the writing line.

60. In a computing typewriter, the combination with the numeral keys, letter keys, carriage, and actuating mechanism thereof, of one or more totalizers adapted to travel laterally across the actuating mechanism, and means operable by the lateral movement of a totalizer to lock the actuating mechanism against further operation when an incorrect total is copied from that totalizer.

61. In a computing typewriter, the combination with the numeral keys, letter keys, carriage, and actuating mechanism thereof, of one or more totalizers adapted to travel laterally across the actuating mechanism, and means operable by the lateral movement of a totalizer to lock the actuating mechanism against further operation when an incorrect total is copied from that totalizer and means for manually removing said lock.

62. In a computing typewriter, the combination with the numeral keys, letter keys, carriage, and actuating mechanism thereof, of one or more totalizers adapted to travel laterally across the actuating mechanism, and means operable by the lateral movement of a totalizer to lock the actuating mechanism against further operation when an incorrect total is copied from that totalizer and means for making said lock operable only at certain points of the writing line.

63. In a typewriter calculating machine, the combination of numeral keys, a traveling carriage, actuating mechanism, a totalizer, said totalizer and actuating mechanism being so arranged that numbers are inserted in said totalizer in the decimal place determined by said traveling carriage, and means controlled jointly by said totalizer and said traveling carriage for automatically displaying a visible signal when a wrong total is copied from the totalizer.

In testimony whereof I have hereunto set my hand in the presence of two subscribing witnesses.

HENRY N. MCKAY.

Witnesses:

JOHN H. HERRING,
W. W. HEALEY.
